UNITED STATES PATENT OFFICE

136,296

DESIGN FOR AN AIRPLANE GLIDER

Bernard Sznycer, Gwynedd Valley, Pa.

Application October 3, 1941, Serial No. 103,627

Term of patent 7 years

To all whom it may concern:

Be it known that I, Bernard Sznycer, a citizen of Poland, residing at Gwynedd Valley, county of Montgomery, State of Pennsylvania, have invented a new, original, and ornamental Design for an Airplane Glider, of which the following is a specification, reference being had to the accompanying drawings, forming part thereof.

Figure 1 is a top plan view of an airplane glider showing my new design.

Figure 2 is a front elevational view.

Figure 3 is a side elevational view of the aircraft.

Figure 4 is a top perspective view thereof.

I claim:

The ornamental design for an airplane glider, substantially as shown.

BERNARD SZNYCER.
